US00D524911S

(12) **United States Design Patent** (10) **Patent No.:** **US D524,911 S**
(45) **Date of Patent:** **** Jul. 11, 2006**

(54) **VALVE**

(75) Inventors: **Terry J. Thompson**, Wakeman, OH
(US); **Terrence M. Fulkerson**,
Brunswick Hills, OH (US)

(73) Assignee: **Nordson Corporation**, Westlake, OH
(US)

(**) Term: **14 Years**

(21) Appl. No.: **29/240,213**

(22) Filed: **Oct. 11, 2005**

Related U.S. Application Data

(63) Continuation of application No. 11/144,878, filed on Jun. 3, 2005.
